ZIGZAG STITCHING MACHINE

Alfred Fredericks, New York, N. Y.

Application July 30, 1941, Serial No. 404,703

2 Claims. (Cl. 112—159)

This invention relates to zigzag sewing machines.

An object of this invention is to provide a sewing machine capable of making multiple rows of zigzag stitching in a single operation.

At the present time in the stitching of elastic tape on a fabric, it is the practice to first stitch one edge of the tape with a single needle zigzag machine and then reverse the work and stitch the other edge. This procedure is not entirely satisfactory as the machines now available frequently make faulty stitches which in certain types of work makes an imperfect article, and as it requires an extra operation on the part of the operator with consequent loss of time.

It is, therefore, another object of this invention to provide a machine of this type which will make at high speed, as an example, multiple lines of uniformly spaced zigzag stitches evenly along the tape in a single traverse of the work through the machine.

A further object of this invention is to provide an improved rotary hook carrier.

A further object of this invention is to provide an improved cam construction for effecting reciprocation of the hook carrier.

A further object of this invention is to provide a machine of this type which will provide spaced lines of zigzag stitches in a uniform manner so that a tape will be flat upon the work and there will be no skipping in stitches, and no bulging of either the tape or work between the lines of stitching.

A further object of this invention is to provide a multiple needle stitching machine for use in connection with the sewing of elastic or other tapes which will eliminate the manual guiding of the tape and at the same time eliminate the possibility of having any of the stitches run over the marginal edges of the tape.

Heretofore attempts have been made to produce multiple needle zigzag machines, but such machines have not been successful and to my knowledge no multiple needle zigzag machine has ever been put to practical use. The prior attempts along this line embodied so many parts as to make the machine cumbersome, subject to frequent breakdown, difficult and unduly expensive to manufacture, and incapable of sufficiently high speed to make them commercially successful. Furthermore, the prior machines frequently broke one or more of the threads, skipped stitches, broke needles, and failed to tightly secure the tape to the work.

It is therefore, a further object of this invention to provide a machine which will overcome the disadvantages of the prior machines and which is so constructed that it may be operated at a very high speed without skipping stitches, breaking threads, or requiring undue repairs, and which will perform its duties in half the time now required of the operator to perform the same work or duties.

10 To the foregoing objects and to others which may hereinafter appear, the invention consists of the novel construction, combination and arrangement of parts as will be more specifically referred to and illustrated in the accompanying drawings, 15 wherein is shown an embodiment of the invention, but it is to be understood that changes, variations and modifications may be resorted to which fall within the scope of the invention as claimed.

In the drawings:

20 Figure 1 is a detail side elevation, partly broken away, of a multiple needle zigzag stitching machine constructed according to an embodiment of this invention.

25 Figure 2 is a bottom plan view of the machine, Figure 3 is a top plan of the forward portion of the bed with the covers for the rotary hook mechanism removed.

Figure 4 is a fragmentary vertical section taken on the line 4—4 of Figure 3.

30 Figure 5 is a fragmentary vertical section taken on the line 5—5 of Figure 3.

Figure 6 is a detail end elevation of the stitching head with the cover plate removed.

Figure 7 is a fragmentary front elevation of the thread tensioning means.

Figure 8 is a fragmentary sectional view taken on the line 8—8 of Figure 7.

Figure 9 is a detail rear elevation of the thread tensioning and releasing mechanism.

Figure 10 is a sectional view taken on the line 10—10 of Figure 8.

Figure 11 is a fragmentary sectional view similar to Figure 8 showing in greater detail the tension release operator.

Figure 12 is a fragmentary rear elevation of the tension release mechanism.

Figure 13 is a fragmentary sectional view taken on the line 13—13 of Figure 2.

Figure 14 is a sectional view taken on the line 14—14 of Figure 13.

Figure 15 is a sectional view taken on the line 15—15 of Figure 13.

Figure 16 is a perspective view of one of the 55 looper saddles.

Figure 17 is a perspective view of the other of the looper saddles.

Figure 18 is a detail top plan of the presser foot.

Figure 19 is a detail side elevation of the presser foot, and

Figure 20 is a fragmentary longitudinal section of the looper operating gears.

Referring to the drawings, the numeral 25 designates generally a head structure including a bed or base 26 which has secured or formed integral with one end thereof an upstanding hollow support 27. A forwardly extending hollow arm 28 is secured to or formed integral with the upper end of the support 27 and is also of hollow construction. A horizontally disposed drive shaft 29 is journalled in the arm 28 and has operatively engaged with one end thereof a pulley or grooved driving wheel 30 with which a belt 31 is adapted to engage. The belt 31 is adapted to be connected with a suitable power mechanism (not shown) for rotating the shaft 29 at the desired speed. The shaft 29 extends to the forward end of the arm 28 and has fixed thereto a crank 32 as shown in Figure 8.

The crank or arm 32 has a pin 33 mounted thereon with which the upper end of a needle carrier reciprocating pitman 34, see Figure 5, is adapted to be connected. The lower end of the pitman 34 is rockably mounted on a pin 35 carried by a clamping block 36 which is mounted on a vertically reciprocable needle carrier shaft 37. The shaft 37 is vertically slidably in a bearing 38 disposed within the hollow head 39.

A needle clamping block 40 is mounted on the lower end of the needle shaft 37, the lower end of the shaft 37 being formed with a reduced portion 41 having opposed flat faces 42. The needle clamping member 40 includes a body 43 having a pair of spaced ears 44 through which a clamping bolt 45 is adapted to engage so as to tightly hold the body 43 on the reduced shaft portion 41. The body 43 is formed with a horizontally disposed forwardly offset lower portion 46 having a pair of spaced apart needle sockets 47 therein for removably receiving a pair of needles 48. The needles 48 are adapted to be removably secured in the sockets 47 by thumb screws 49 which are threaded into the offset portion 46.

The needle shaft 37 and the clamping member 40 are laterally shifted in order to provide for a zigzag stitch structure by the following means: The bearing 38 is connected with a lower bearing 50 by means of an offset connecting member 51 and the bearing member 50 is formed at its forward side with a forwardly extending arm or lug 52. The lug or arm 52 is provided with an elongated horizontally disposed slot 53 in which a headed pin 54 is adapted to loosely engage. The pin 54 is adapted to be threaded into the lower portion of the head 39.

An upwardly extending supporting lever or arm 52a is fixed to or formed integral with the lug 52 and is provided at its upper end with a bushing 52b through which a pivot pin 52c engages. The pin 52c is threaded into the upper portion of the head 39 as shown in Figure 6. In this manner the bearings 38 and 50 are swingably supported from the head 39.

The bearing member 50 is also formed with a pair of inwardly extending ears 55 between which the forward downwardly offset end 56 of a pitman 57 is adapted to be pivotally engaged. A pivot pin 58 engages through the ears 55 and the forward portion of the pitman 57. The pitman 57 is formed with an upwardly offset inner por-

tion 59 connected with the forwardly and downwardly offset portion 56 by means of an integral connecting member 60. The rear portion of the pitman 57 is formed with a split loop similar to the loop structure shown in Figure 14 which is adapted to be connected with an adjustable eccentric member 61. The details of construction of the eccentric structure 61 are similar to the details of construction of the eccentric for shifting the shuttle mechanism and will be described in greater detail hereafter.

The inner portion of the supporting arm 28 is formed with a forwardly offset annulus 62 on which a cover plate 63 is adapted to be mounted by fastening devices 64. A top cover plate 65 is mounted on the upper portion of the supporting arm 28 and is secured in position by means of at least one fastening device 66 as shown in Figure 1.

The drive shaft 29 has mounted thereon in the upper portion of the supporting member 27 a beveled gear 67. The beveled gear 67 meshes with a beveled gear 68 which is mounted on the upper end portion of a vertical countershaft 69 which is journalled in bearings 70 carried by the interior of the hollow supporting member 27. The lower end of the countershaft 69 has secured thereto a lower beveled gear 71 which meshes with a beveled gear 72 secured to a horizontally disposed shuttle operating shaft 73. The rear end portion of the shaft 73 is journalled in a bearing 74 which is carried by and extends downwardly from the under side of the bed or base 26.

The shaft 73 has fixed thereto a worm 75 which is held against endwise movement on the shaft 73 by means of a pair of collars 76 and 77. The worm 75 is adapted to mesh with a worm gear 78 which is mounted on a shaft 79. The shaft 79 is disposed in vertical position and is journalled at its upper end in a bearing 80 which is secured by fastening devices 81 to the under side of the base or bed 26. The lower end of the shaft 79 is journalled in a bearing plate 82 which is secured by fastening devices 83 to a downwardly extending lug 84. The lug 84 is secured by fastening devices 85 to the under side of the bed or base 26. A thrust washer or plate 86 is interposed between the lower side of the worm gear 78 and the adjacent face of the bearing member 82. The worm gear 78 may be keyed or otherwise mounted on the shaft 79 for effecting rotation of the shaft 79. A plate 87 which is formed with a hub 88 is mounted on the shaft 79 above the worm gear 78 and is secured against rotation relative to the shaft 79 by set screws 89. A cam plate 90 is adapted to be disposed in face abutting relation with respect to the plate 87 and the plate 90 is secured to the plate 87 by a fastening device in the form of a bolt 91. The plate 90 is formed with an elongated arcuate opening or slot 92 at a point diametrically opposite from the bolt 91 through which a second bolt 93 is adapted to engage. The slot 92 provides a means whereby the plate 90 may be eccentrically adjusted with respect to the plate 87 and held in its eccentric adjusted position.

An annular cam member or eccentric 94 is fixed to or formed integral with the cam plate 90 and is provided with a relatively large bore 95 through which the shaft 79 loosely engages. The plate 90 is also formed with a bore 96 which is formed as a continuation of the bore 95 in order to permit the eccentric adjustment of the cam member 94 and the plate 90 relative to the plate 87. The rear end portion 97 of a shuttle mechanism op-

erating pitman 98 is adapted to encompass the cam member 94 and preferably, the rear end portion 97 of the pitman 98 is split and formed with a pair of ears 99 and 100 through which an adjusting screw 101 extends in order to take up wear in the annulus 97.

In order to provide a means whereby the reciprocal movement of the pitman 98 may be varied, I have provided a threaded cam adjusting screw 102 which is threaded into a boss or enlargement 103 carried by the upper side of the cam plate 90. The screw 102 has formed on the inner end thereof a reduced diameter pin 104 which is engageable in a concave recess 105 formed in the periphery of the shaft 79. The plate 90 is formed at a point diametrically opposite from the enlargement or lug 103 with a second lug or enlargement 106 having a bore 107 therethrough. A spring-pressed plunger 108 is slidable in the bore 107 and is formed at its inner end with a concave portion 109 slidably engaging the periphery of the shaft 79. The plunger or plug 108 is formed at its outer end with a reduced stem 110 about which the inner end of a plug tensioning spring 111 is adapted to engage. The outer end of the spring 111 engages about the reduced end portion 112 of a plunger or plug tensioning screw 113 which is threaded into the outer end portion of the lug or enlargement 106. The cam structure 61 for reciprocating the pitman 98 is similar in every detail to the cam structure hereinbefore described and shown in greater detail in Figures 13, 14 and 15.

By providing an annular cam or eccentric 94 as hereinbefore described, the pitmans 57 and 98 will be reciprocated back and forth in a smooth operation so as to eliminate any vibration of the machine when operating at a very high speed. It will be understood that the machine embodying this invention is operated at a very high speed in order to rapidly turn out the work which is operated upon.

The forward end portion of the pitman 98 is connected by means of a pivot member 114 to a slide member 115. The slide member 115 slidably engages the under side of a downwardly offset housing 116 carried by the bed or base 26. A guide member 117 which is carried by a right angularly disposed plate 118 engages one edge of the slide 115 and is secured to the rear side of the housing 116 by fastening members 119. A second plate or guide 120 is secured by fastening devices 121 to the bottom wall 122 of the housing 116.

A shaft 123 is disposed in axial alignment with the shaft 73, being rotatably and slidably mounted in a pair of bearings 124 and 125 which are fixed to or formed integral with the under side of the bed or base 26. The shaft 73 has secured to the end thereof adjacent the end of the shaft 123 a coupling plate 126 formed with a hub 127 secured by fastening members 128 to the shaft 73. The plate 126 has fixedly mounted therein a plurality of circumferentially spaced apart coupling pins 129 which slidably engage in openings 130 formed in a second coupling plate 131. The coupling 131 is provided with a hub 132 fixed by one or more fastening devices 133 to the shaft 123. The coupling pins 129 are of such a length as to provide for rotation of the shaft 123 for the length of movement of the slide member 115.

The shaft 123 has fixedly mounted thereon a pair of worm members 134 and 135 which are disposed in spaced apart relation. The shaft 123

is formed in the periphery thereof with a longitudinally extending groove 136 within which fastening members 137 and 138 engaging through the worm members 134 and 135 respectively are adapted to engage so that the worm members will be held against rotary movement and also endwise movement on the shaft 123. A grooved member 139 is interposed between the adjacent ends of the worm members 134 and 135 and is secured to the shaft 123 by a fastening member 140 which engages at its inner end within the channel or groove 136 as shown in greater detail in Figure 20.

In order to provide a means whereby the shaft 123 will be moved endwise coincident with the reciprocation of the slide member 115, I have provided an arcuate bar 141 which is adapted to engage in the groove of the grooved member 139. The arcuate holding member 141 is formed with an outer base 142 which is secured by fastening members 143 which are threaded into the slide member 115. The worm 134 meshes with a worm gear 144 which is mounted on a looper shaft 145. The looper shaft is journaled at its lower end through an adjustable plate 146 which is formed with an elongated slot or opening 147. A pair of fastening members 148 are extended through the slot 147 and threaded into the slide 115 for holding the plate 146 in lengthwise adjusted position with respect to the slide 115.

The worm 135 meshes with a worm gear 149 which is mounted on the lower end of a vertical looper shaft 150. The shaft 150 is journaled through an adjustable lower bearing plate 151 having an elongated slot 152 therethrough. A pair of fastening members 153 engage through the slot 152 and are threaded into the slide member 115 so as to hold the bearing plate 151 in longitudinally adjusted position with respect to the slide 115. The slide 115 is formed with a long slot or opening 154 through which the two shafts 145 and 150 loosely extend. The bottom wall 122 is also formed with an elongated opening 155 through which the shafts 145 and 150 loosely engage. The two long slots 154 and 155 are of sufficient length to permit the endwise movement of the slide 115 and also to permit adjustment of the shafts 145 and 150 relative to each other to provide for the desired looping of the threads carried by the shuttles associated with the looper shafts.

A saddle member or plate 156 is slidably mounted on the upper side of the bottom wall 122 of the housing 116 and is provided with a pair of parallel spaced apart slots 157 through which clamping bolts 158 engage for adjustably clamping the saddle 156 on the upper side of the wall 122. The saddle 156 has fixed thereto a bearing or bushing 159 through which the shaft 145 is journaled. A second saddle or plate 160 having a pair of parallel elongated slots 161 is slidably secured by clamping bolts 162 to the upper side of the bottom wall 122 in spaced apart relation with respect to the saddle 156. The saddle or plate 160 has fixed thereto a depending bearing or bushing 163 through which the looper shaft 150 is journaled. The two bushings 159 and 163 loosely extend through the elongated slots or openings 154 and 155 formed in the slide 115 and the bottom wall 122 respectively.

A plate 164 is disposed on the upper side of the saddle 156 and has formed integral therewith an ear 165 provided with an elongated slot 166 through which a fastening member 167 engages.

The fastening device 167 provides a means whereby the plate 164 may be circumferentially adjusted with respect to the shaft 145. A bobbin receptacle 168 is mounted above the plate 164 and a loop-forming hook 169 is secured to the shaft 145 below the receptacle 168. An oscillating loop finger 170 is interposed between the base of the hook structure 169 and the plate 164 and coacts with the hook 169 in forming the desired loop for looping the thread below the work. The receptacle 168 is formed with a radially extending lug 171 which is adapted to loosely engage in a downwardly opening substantially V-shaped notch 172 which is formed in the under side of a rotation restraining arm or finger 173. The arm or finger 173 is secured to an upright supporting member 174 formed with a base plate 175 secured by fastening devices 176 in a rabbet or cutout 177 carried by the adjacent edge portion of the saddle 156, as shown in Figure 16.

The thread engaging the hook 169 is adapted to slide between the lug 171 and the marginal faces of the V-shaped opening or recess 172 in forming the completed loop. A bobbin 178 is adapted to rotatably engage within the receptacle 168 and the bobbin 178 is frictionally held against rotation with respect to the receptacle 168 by means of a spring 179 which is carried by the receptacle 168. The constructions of the receptacle 168, the hook 169 and the loop-forming finger 170 are conventional. The finger 173 is substantially straight and extends rearwardly at substantially a tangent to the bobbin 178 as shown in Figure 3. The thread which is carried by the associated needle is adapted to ride along the outer edge 180 of the rotation restraining finger 173 and pass over the rear end of this finger as the hook 169 engages and pulls the thread rearwardly of the retaining finger 173.

The saddle 160 has mounted on the upper surface thereof a plate 181 formed with an outwardly extending ear 182 having a notch 183 therein for receiving a clamping bolt or screw 184. The bolt or screw 184 is threaded into the saddle 160 and the plate 181 is adapted to be circumferentially adjusted with respect to the hook shaft 150 by swinging of the ear 182. A bobbin receptacle 185 is mounted above the plate 181 and is provided with a radially and outwardly extending lug or finger 186 adapted to engage in a downwardly opening substantially V-shaped notch 187 carried by a rotation restraining finger 188. The finger 188 includes a rear portion 189 extending in substantially parallel relation with the movement of the work and also includes an obtusely disposed extension 190 which is provided with the notch 187 in the rear portion thereof. The finger 188 is supported in operative position above the receptacle 185 by means of an upright supporting member 191 carried by a base 192. The base 192 is secured by fastening devices 193 in a rabbet or cutout 194 which is formed in the inner portion and the upper surface of the saddle 160. A loop-forming hook 195 is fixed to the shaft 150 and rotates about the receptacle 185. An oscillating loop-forming finger 196 is interposed between the base of the hook 195 and the plate 181 and coacts with the hook 195 in forming the loop of the two threads from the shuttle 196 and the associated needle.

The two saddles 156 and 160 are adapted to be reciprocated with the slide 115 and preferably, a plate 197 is secured by fastening devices 198 to the upper side of the bottom wall 122 and is provided with a pair of guide plates 199 and

200 which extend over the upper faces of the saddles 156 and 160, respectively, so as to slidably hold the saddles on the bottom wall 122. The guide member 199 is secured by fastening devices 201 to the plate 197 and the guide member 200 is secured by fastening devices 202 to the upper face of the plate 197.

The work which is being moved through the machine is moved by means of a work-feeding member 203 which is constructed in the form of an elongated serrated bar 204 secured to an upwardly extending arm 205. A plate 206 is mounted on the table 26 and is formed with an elongated opening 207 within which the feeding member 203 loosely engages. A pair of laterally offset feeding members 208 and 209 are disposed in parallel relation with respect to the feeding member 203 and are formed integral with the extension 205. The feeding members 208 and 209 are adapted to be disposed substantially in alignment with the two needles 48 so as to feed the material directly to the needles. The feeding members 208 and 209 are substantially shorter in length than the feeding member 203, the feeding member 203 being adapted to extend between the two needles 48. The plate 206 is formed with a pair of slots 210 within which the feeding members 208 and 209 slidably engage. The feeding members 203, 208 and 209 are carried by an elongated arm 211 which is secured by fastening devices 212 to a horizontally disposed feed operating arm 213. The arm 213 is slidable through an opening 214 formed in the forward wall 215 of the housing 156. The arm 213 at its forward end is provided with a downwardly extending member 216 which may loosely engage in a slot or cutout 217 formed in the plate 197.

The rear end of the arm 213 is formed with a socket 218 in which a disc-shaped element 219 carried by a lever 220 rockably engages. The lever 220 is fixed to a rock shaft 221 which is operatively connected with the drive shaft 29, the movement of the rock shaft 221 and its connection with the drive shaft being of conventional construction.

A horizontally and rearwardly extending guide member 222 is disposed in parallel relation with the arm 213 and is secured to or formed integral with the lower end of the extension 216, as shown in Figure 5. A slide or block 223 is slidably disposed between the arm 213 and the guide member 222 and is formed at the upper and lower edges thereof with depending flanges 224 for engagement on the opposite faces of the arm 213 and the guide member 222. The block or slide 223 is formed with a socket 225 in which a pivot member 226 carried by a rock arm 227 rockably engages. The arm or lever 227 is fixed to a rock shaft 228 which is operatively connected with the drive shaft 29 and coacts with the rock shaft 221 in effecting vertical movement of the feeding members 203, 208 and 209 simultaneously with the back and forth movement or reciprocation thereof.

A presser foot generally designated as 229 is adapted to engage above the table 26 and above the feeding members 203, 208 and 209. The presser foot 229 is secured in a downwardly opening slot 230 formed in the lower end portion of a presser foot shaft 231. The presser foot 229 is secured in the slot 230 by a fastening device 232. The shaft 231 is vertically adjustable in a cylindrical guide 233 which is carried by the head 39 rearwardly of the needle shaft 37. The shaft 231 has fixed thereto a rearwardly extend-

ing arm 234 which extends through the rear wall 235 of the head 39, and the shaft 231 is moved to an uppermost inoperative position by means of a shaft operating lever 236 pivotally mounted on a pivot 237 engaging between a pair of ears 238. The lever 236 is formed with a cam portion 239 engageable with the under side of the lug 234 as shown more specifically in Figure 6. The shaft 231 is spring-pressed in a conventional manner to a lowermost operative position.

The presser foot 229 includes a flat plate 240 which is provided on the under side thereof with a pair of downwardly extending guide ribs 241 spaced apart a sufficient distance so that a tape T may slidably engage between the pair of ribs 241. A transversely extending flat strip or bar 242 extends between the two ribs 241 adjacent the forward end portion thereof so as to form a narrow guide channel 243 through which the tape T is adapted to be threaded. The forward end portion of the plate 240 is provided with an upwardly extending body 244 which forms a guide at the forward portion of the foot structure 229. The plate 240 is provided with a pair of elongated openings 245 positioned on opposite sides of the longitudinal center thereof through which the needles 48 are adapted to loosely engage. The slots 245 are of sufficient length so as to permit the threads and the needles 48 to laterally shift while the foot 24 remains stationary. The plate 240 is provided with a pair of upstanding lugs or ears 246 between which a block 247 carried by a flat stem 248 is adapted to loosely engage. The block 247 is of substantially triangular configuration in side elevation and has a pivot pin 249 extending therethrough. The pivot pin 249 is also extended through the ears 246 so that the plate 240 will be pivotally supported from the stem 246. The plate 240 is limited in its rocking movement with respect to the block 247 by the flat lower face 250 of the block 247. The plate 240 is constantly urged to a substantially right angularly disposed position with respect to the stem 248 by means of a flat leaf spring 251 which is secured at one end as by a fastening device 252 to the forward face of the block 247. The forward or free end of the spring 251 engages the arcuate upper face 253 of the lug or rib 244. By rockably mounting the plate 240 on the stem 248, the plate or foot member 240 may rock upwardly when seams or multiple thicknesses of material are passing beneath the foot member 240.

A thread tensioning structure generally designated as 254 is disposed on the forward side of the supporting arm 28 adjacent the head 39. The tensioning structure 254 includes a plate 255 formed with an upwardly extending ear 256. A fastening device 257 extends through the ear 256 and is threaded into a forwardly projecting boss 258 which is fixed relative to the supporting member or arm 28. In the present instance, there are two needles 48 and two strands or threads 259 and 260 which are threaded through the needles 48 and tensioned by the tensioning structure 254. An upstanding post 261 is fixed to the upper side of the supporting arm 28 and is provided with a pair of right angularly disposed and vertically spaced apart openings 262 and 263 through which the thread 259 is threaded. The post 261 provides a combined guide and tensioning means for the thread 259.

A second upstanding post 264 is also fixed to the upper side of the supporting arm 28 and is provided with a pair of vertically spaced guide

openings 265 and 266 through which the thread 260 is threaded.

The plate 255 has secured thereto an open eye or loop 267 disposed adjacent a spring-pressed tensioning member 268. The thread 259 is adapted to engage through the eye 267 and engage over the tensioning member 268 as shown in Figure 1. The thread 259 is then passed between a pair of dished washers which are under the tension of a spring 269. The details of construction of the washers 270 are more specifically shown in Figures 9 and 10. The thread 260 is extended from the post 264 and then passed through a guide eye 271 disposed adjacent a spring-pressed tensioning member 272. The thread is then extended from the tensioning member 272 to a thread tensioning means 273. The tensioning means 273 includes an inner washer 274 and an outer washer 275. The washers 274 and 275 are mounted on a threaded shaft 276 which is fixed to the plate 255. The plate 255 is formed with a tapered opening 277 in which the rear end portion of the shaft 276 engages, and the shaft 276 is upset as at 278 so as to firmly secure the shaft 276 on the plate 255. The shaft 276 (see Figure 10) is preferably provided with an annular flange 279 which abuts against the forward side of the plate 255.

An outer washer 280 is loosely mounted on the shaft or supporting member 276 and is provided with a diametrically disposed bar 281 which slidably engages in an elongated slot 282 formed in the shaft or supporting member 276. The supporting member 276 is provided with a bore 283 extending from the outer end portion thereof and the enlarged body portion 284 of a tension releasing pin 285 slidably engages in the bore 283. The outer end portion of the body 284 abuts against the bar 281 so that outward movement of the pin 285 and the body 284 will forcibly move the washer 280 outwardly against the tension of a tensioning spring 286. A spring tensioning nut 287 is threaded onto the supporting member 276 and engages against the outer end of the spring 286. The thread tensioning structure including the pair of washers 270 and the spring 269 with the supporting member 280 therefore is similar in every detail to the structure shown in Figures 8 and 10 with respect to the thread tensioning member 273. The pin 285 slidably engages through an opening 288 formed in the plate 255 and the rear end of the pin 285 projects rearwardly of the rear face of the plate 255.

A pin operating member generally designated as 290 is pivotally supported from supporting pins 291 fixed to the plate 255 and extending rearwardly therefrom. The pin operating member 290 is interposed between the rear side of the plate 255 and the forward side of the supporting member 28. The pin operating member 290 is formed with an obtusely disposed lever 292 which is disposed in the path of the movement of a tension releasing pin 293 which is slidably in an opening 294 formed in the head 39 below the forward end of the shaft 29 and the crank 32. The pin operating member 290 is formed with an extension 295 which terminates in a position confronting the rear end of one of the pins 285 and the arm or lever 292 is disposed in a confronting position with respect to the other of the pins 285.

The tension releasing pin 293 has an annular groove 296 formed in the peripheral surface thereof at a point intermediate the ends thereof 75 and a pin operating member generally designated

as 297 loosely engages in the groove 296. The pin operating member 297 is constructed in the form of a parti-spherical body 298 which loosely engages in the groove 296, and a second parti-spherical body 299 which is substantially larger in diameter than the body 298 so as to thereby form a shoulder 300 which is adapted to engage the peripheral surface of the pin 293 outwardly from the groove 296. The parti-spherical body 299 is formed with a flat cam face 301 which is disposed in the path of rotation of a semi-circular cam member 302 which is fixed to the shaft 29 and may be formed integral with the crank or arm 32. The forward end of the supporting member 28 is formed with an elongated opening 303 within which the pin operating member 297 movably engages. The pin operating member 297 is adapted to contact with the leading edge of the cam 302 so that the operating member 297 and the pin 293 will be moved rearwardly thereby. The flat face 301 of the pin operating member 297 will slidably engage the arcuate surface 304 of the cam 302 and when the arcuate surface 304 rides off of the flat face 301, the operating member 297 will be released abruptly from the cam 302 so that the pin 293 may be quickly shifted forwardly under the tension of a spring member 305. The spring member 305 is tensioned upon rearward movement of the pin 293, being carried by a horizontally disposed supporting member 306 which is fixed to one side of the foot operating lug 234. The forward face of the spring member 305 is bevelled, as at 307, so that the pin 293 will be moved forwardly upon raising of the foot lever 236 and the lug 234.

The forward end of the pin 293 is formed with a round nose 308 confronting the lower end of the operating member 290 and the rear end of the pin 293 is formed with a relatively pointed portion 309. Preferably, the bore 294 is provided with a V-shaped lower portion 310 which is adapted to prevent rotary movement of the pin 293 in the bore 294. When the pin 293 is released by the cam 302 riding off of the flat face 301 of the pin operating member 297, the spring 305 will move the pin 293 forwardly so as to strike the operating member 290. Forward rocking of the operating member 290 will push the two pins 285 forwardly in the supporting members 276 and 288 and relieve the washers 274 and 275 of the tension of the spring 286. This release of tension on the two threads 259 and 260 is effected just before the rockable thread pulling member 311 mounted on the forward portion of the supporting member 28 reaches the uppermost position in its rocking movement. This momentary release of the tension on the two threads has been found necessary in order to permit the thread to be properly looped and pulled over against the under face of the work. Without this release of tension, the thread pulling member 311 has a tendency to break the thread.

A grooved thread guiding member 312 is mounted on a supporting shaft 313 carried by a downwardly extending arm 314 formed integral with the plate 255. The two threads 259 and 260 are adapted to engage in the groove 315 of the grooved member 312 and in order to provide a means whereby the thread will not readily be able to become disengaged from the grooved member 312, I have provided a forwardly extending spring finger 316 which is struck from the rear wall 317 of the grooved member 312 and extends forwardly into an elongated slot 318 formed in the front wall 319 of the grooved member 312. The member 312 is formed with a pair of elongated arcuate registering slots 320 in the walls 317 and 319 through which a holding screw 321 engages so as to hold the grooved member 312 against rotation on the shaft 313. The shaft 313 is formed rearwardly of the plate 255 with an enlarged cylindrical body 322 which is adapted to loosely engage in a socket 323 formed in the forward side of the supporting member 28.

A reduced extension 324 extends rearwardly from the enlarged portion 322 and is adapted to set in a forwardly opening socket 325 which is formed in the base of the socket 323. A coil spring 326 is disposed about the enlarged part 322 of the shaft 313 and has one end thereof hooked into a groove or recess 327 formed in the periphery of the enlarged shaft member 322 adjacent the rear end thereof. The coil spring 326 is formed with a loop 328 which overlies the two walls 317 and 319 of the grooved member 312 and the spring is also formed with an eye or loop 329 engaging about the shaft 313 outwardly from the grooved member 312. A nut 330 is threaded onto the threaded outer portion of the shaft 313 and is adapted to hold the eye 329 in the desired position with respect to the outer side of the grooved member 312.

After the threads pass upwardly from the grooved member 312, they are adapted to engage an arcuate thread guiding arm 331 which is secured to the forward side of the head 39 at a point below the pulling member 311. The two threads are then extended through the eye of the pulling member 311 and brought downwardly through a pair of openings formed in a forwardly extending flange 332 which forms a part of the guide member 331. The threads are then extended downwardly through a lower guide member 333 which is fixed by a fastening device 334 to the head 39. The threads are extended from the loosed guide member 332 to the eyes of the needles 48.

A tape guide member generally designated as 335 is carried by the head 39 and includes a split elongated loop 336 which is carried by a forwardly extending supporting arm 337. The rear end of the arm 337 is formed with an eye 338 which is secured by a thumb screw 339 to the head 39. The looped guide member 336 is disposed in a position overlying the presser foot 229 so as to evenly guide the tape T to the forward end of the presser foot 229. The tape which engages through the guide loop 336 is taken from a supply roll which may be supported in any suitable manner above and rearwardly of the stitching machine.

With a guide structure of this kind, the tape is fed to the machine in such a manner as not to interfere in any way with the movement of the work through the machine. At the present time, it is the practice to support the tape at a point below the table or bed 26 and with this procedure it is necessary to insert the work below the tape. However, with a tape guiding means including a tape guiding presser foot as hereinbefore described, the tape which is being stitched to the work is free of the work until it is finally stitched thereto. The operator of the machine, therefore, can insert the several pieces of work rapidly beneath the presser foot as the work is moved by means of the feeding structure.

In the use and operation, the machine is adapted to be mounted on a suitable supporting structure and operatively connected with a power source through the flexible belt 31. It will be

understood that a suitable clutch mechanism may be mounted within the head of the machine in association with the shaft 29, such clutch mechanism being conventional in construction. The work is inserted beneath the presser foot 229 under the tape T and at the time the needles 48 move downwardly through the tape and the work, the needles 48 move downwardly in a straight vertical line. The two threads are looped beneath the work by the looper mechanism hereinbefore described, and the needles then move upwardly.

During the upward movement of the needles 48 the two cam structures 61 and 94 will shift the needles 48 and the shuttles 178 and 196 laterally in the same direction. At the time the pulling member 311 reaches substantially the uppermost position, the tension on the two threads is released by the releasing pin 293. During the upward movement of the needles, the cam member 302 will initially strike the pin operating member 297 so as to shift the operator 297 and the pin 293 rearwardly or to the left as viewed in Figures 8 and 11.

The rearward shifting of the pin 293 will bring the rear end 309 thereof into engagement with the spring 305 so as to place this spring under tension. The spring 305 is a relatively heavy spring so that when the operator 297 is released, the spring 305 will quickly shift the pin 293 forwardly. After the pin 297 is moved rearwardly or to the left by the leading edge of the cam 302 the arcuate or peripheral surface of the cam 302 will ride over the flat face 301 of the operator 297 and hold the operator 297 with the pin 293 in a rearward position under the tension of the spring 305. When the cam 302 rides off of the flat face 301 of the operator 297 the pin 293 is suddenly released and forced forwardly by the spring 305 into engagement with the tension release lever 292. The forward rocking of the lever 292 will force the two releasing pins 285 forwardly so as to relieve the two tensioning members 270 and 273 of the tension of their respective springs.

A machine has been constructed according to this invention and operated at a relatively high speed and has been found to provide more uniform stitching on the opposite marginal edges of a tape than is possible by either a single zigzag stitching machine, such as is now available, or a multiple needle stitching machine which does not embody this invention. In fact, there does not appear to be any multiple needle machine available for producing a zigzag stitch.

What I claim is:

1. A multiple needle stitching machine com-

prising a head, a bed plate integral with said head, a drive shaft journaled in said head, a needle carrier, means connected with said drive shaft for vertically reciprocating said carrier, 5 means supporting said carrier for lateral shifting, means supported by said head and driven by said drive shaft for laterally shifting said carrier, a vertical shaft, gear means connecting said vertical shaft with said drive shaft, a horizontal driven shaft rotatably carried by said bed plate, gear means connecting said driven shaft with said vertical shaft, a second driven shaft aligning with said first driven shaft, a slidable connection between said first and second driven shafts, a 10 slide plate below said bed, means slidably securing said plate to said bed, a pair of looper members carried by said slide plate, means for adjusting said looper members relative to each other on said slide plate, gear means connecting said latter members with said second driven shaft, and means connected with said first driven shaft and with said slide plate for reciprocating the latter, reciprocation of said slide plate also reciprocating said second driven shaft relative to said first driven shaft.

2. A multiple needle stitching machine comprising a head, a bed plate integral with said head, a drive shaft journaled in said head, a needle carrier, means connected with said drive shaft for vertical reciprocating said carrier, 15 means supporting said carrier for lateral shifting, cam means supported by said head and driven by said drive shaft for laterally shifting said carrier, a vertical shaft, gear means connecting said vertical shaft with said drive shaft, a horizontal driven shaft rotatably carried by said bed plate, gear means connecting said driven shaft with said vertical shaft, a second driven shaft aligning with said first driven shaft, a slidable connection between said first and second driven shafts, said slidable connection comprising a pair of confronting coupling plates fixed to said first and second driven shafts, pins fixed to one of said coupling plates slidably engaging the other coupling plate, a slide plate below said bed, means slidably securing said slide plate to said bed, a pair of looper members carried by said slide plate, gear means connecting said latter members with said second driven shaft, and cam means connected with said first driven shaft and with said slide plate for reciprocating the latter, reciprocation of said slide plate also reciprocating said second driven shaft relative to said first driven shaft.

ALFRED FREDERICKS.
